UNITED STATES PATENT OFFICE.

LEVI SAMUEL BROWN, OF UNION CITY, TENNESSEE.

HORSE-DETACHER.

SPECIFICATION forming part of Letters Patent No. 356,097, dated January 18, 1887.

Application filed September 8, 1886. Serial No. 213,025. (No model.)

To all whom it may concern:

Be it known that I, LEVI SAMUEL BROWN, a citizen of the United States, residing at Union City, in the county of Obion and State 5 of Tennessee, have invented a new and useful Improvement in Horse-Detachers, of which the following is a specification.

My invention relates to an improvement in horse-detachers; and it consists in the peculiar construction and combination of devices 10 that will be more fully set forth hereinafter, and particularly pointed out in the claims.

In the drawings, Figure 1 is a perspective view of a horse-detacher embodying my improvements, and showing a portion of the whiffletree to which it is attached. Fig. 2 is a vertical sectional view of the same.

A represents the whiffletree, and B represents a ferrule, which is made of iron or other 20 suitable metal and is fitted on the end of the whiffletree. The ferrule is provided on its inner end with a projecting tongue, C, which extends longitudinally on the whiffletree and fits in a groove, D, that is made therein. On 25 one side of the ferrule is formed a tube or sleeve, E, from the outer end of which extends a curved arm, F. The outer end of the arm F is provided with an opening, G, which aligns with the bore of the sleeve or tube E.

H represents a sliding bolt which passes 30 through the sleeve or tube E, and is adapted to enter the opening G of the arm, so as to close the open side of the latter. This bolt is provided at its inner end with an arm, I, which extends along one side of the whiffletree 35 and is provided with a longitudinal slot, K. At the inner end of the said slot is formed an eye, L.

M represents a screw which extends through 40 the slot K and enters the whiffletree, and the head of the said screw which bears against the outer side of the arm I is provided with an opening, m.

N represents the spring, which has one end 45 attached to the rear end of the bolt, and the said spring extends rearwardly, passes through the opening m, and is provided near its rear end with a shoulder, n. At the extreme rear end of the spring is formed an eye, n'.

O represents the cord which is attached to 50 the eye of the spring, extends through the eye

of the bolt, and is guided through an eye, P, on the rear side of the whiffletree. The other end of the said cord extends to a convenient point in the vehicle, where it can be readily 55 reached by the driver.

The operation of my invention is as follows: The opening in the rear end of the trace is placed in the curved arm F, and the bolt is then extended through the said opening and caused 60 to enter the opening G at the outer end of the arm. This causes the shoulder n of the locking-spring N to engage the eye or opening of the screw M, thereby locking the bolt and preventing it from becoming accidentally de- 65 tached from the trace. In order to release the trace, and thereby detach the horse, the driver pulls upon the cord O, which draws the rear end of the spring N toward the rear end of the arm I, thus causing the shoulder n 70 of the said spring to first disengage the opening m of the screw, and a continued pull upon the said cord causes the bolt to slide rearwardly, and thus release the trace, as will be very readily understood. Screws C' pass 75 through openings which are made in the tongue C and enter the whiffletree, so as to secure the ferrule firmly on the end of the whiffletree.

A horse-detacher thus constructed is ex- 80 tremely cheap and simple, is very durable, is easily attached to the whiffletree, and does not work loose or rattle.

Having thus described my invention, I claim—

1. The combination, with the whiffletree, of the ferrule attached thereto and having the tube or sleeve E and the curved arm F at the outer end thereof, the bolt H, fitting in the tube or sleeve and having the rearward-extending arm provided with the slot K, the screw extending through the said slot and entering the whiffletree and provided with the eye or opening m, and the spring N, attached to the sliding bolt and extending through the eye or opening m, the said spring having the shoulder n near its outer end, for the purpose set forth, substantially as described. 95

2. In combination with the tube E and arm F, attached to a whiffletree, the sliding bolt H, the spring attached to the bolt and moving therewith, the extension or arm I of the bolt, 100

and the operating cord O, connected to the arm I, and the spring N, as set forth.

3. The combination, with the whiffletree having the eye m and the arm or keeper F, of the 5 sliding bolt H, having the spring N, provided with the detent-shoulder n, to engage the eye m and lock the bolt in its extended position, substantially as described.

In testimony that I claim the foregoing as my own I have hereto affixed my signature in presence of two witnesses.

LEVI SAMUEL BROWN.
